DESIGN FOR A FOOTREST

Henry C. Stoll, Bronx, N. Y., assignor of one-half to Rudolph Keil, Bronx, N. Y.

Application August 13, 1938, Serial No. 79,317

Term of patent 7 years

To all whom it may concern:

Be it known that I, Henry C. Stoll, a citizen of the United States, residing at Bronx, county of Bronx, State of New York, have invented a new, original, and ornamental Design for a Footrest, of which the following is a specification, reference being had to the accompanying drawing, forming part thereof.

The single figure is a perspective view of a footrest, showing my new design.

I claim:

The ornamental design for a footrest, substantially as shown.

HENRY C. STOLL.
